UNITED STATES PATENT OFFICE.

HENRY DUNHAM, OF ABINGTON, MASSACHUSETTS.

IMPROVEMENT IN NAIL-DRIVING MACHINES.

Specification forming part of Letters Patent No. 154,129, dated August 18, 1874; application filed December 10, 1873.

To all whom it may concern:

Be it known that I, HENRY DUNHAM, of Abington, in the county of Plymouth and State of Massachusetts, have invented certain new and useful Improvements in Machines for Driving Headed Nails; and I do hereby declare the following to be a full, clear, and exact description of the invention, such as will enable others skilled in the art to which it pertains to make and use it, reference being had to the accompanying drawings, which form part of this specification.

My invention relates to certain improvements in nail-driving machines for boots and shoes, as is herein more fully shown and described.

On the drawings, Figure 1 represents a front elevation of my invention. Fig. 2 represents a side elevation. Fig. 3 represents a longitudinal section on the line A B, shown in Fig. 1; and Fig. 4 represents a longitudinal section on the line C D, shown in Fig. 2.

Similar letters refer to similar parts wherever they occur on the different parts of the drawings.

a represents the stand of the machine, to which the head *b* is secured. In upper end of the head *b* are made bearings *c c* for the cam-shaft *d*, that is set in rotary motion by means of power applied to the pulley *e*, or otherwise, as may be practical. To the shaft *d* is secured a number of cams, *f*, *g*, *h*, and *i*, as shown. The cam *f* is grooved on its face, and is made to operate the driver-bar *f'*, that is for this purpose provided in its upper end with a projection or roller, *f''*, that engages into the groove on the face of the cam *f*. The cam *g* is also grooved on its face and operates the feed-bar *g'*, that is for this purpose provided in its upper end with a projection or roller, *g''*, that engages into the groove on the face of the cam *g*. The feed-bar *g'* is made to slide in guides in the rocking head *h'*, that is made to rock around a fulcrum, *k*, in the frame *b*. The head *h'* is made to rock and operated by the cam *h*, acting on a projection, *h''*, that forms a part of the rocking head, *h'*, as shown in Fig. 4, and a side spring, *h'''*. The last cam *i* operates a rocking lever, *i'*, the lower end of which operates a suitable nail picker or feeder, *l*, that picks the nails from the inclined ways

m m and delivers them, one at a time, to the hollow tube *n*, from which the nail drops through a perforation in the lower end of the feed-bar *g'*, in the space between the movable dies *o o*, where it is held in a proper position till the driver *f''* descends and forces the nail into the sole of the boot or shoe. The movable dies *o o* are forced toward each other by means of side springs *p p*, secured to the lower end of the rocking head *h'*, as shown. The dies *o o* are made to slide outward when the driver *f''* descends, for the purpose of allowing the head of the nail to pass between them, and are forced back to their original positions, so as to embrace and hold the point of the nail in an exact position, till the driver again descends and drives the said nail into the sole of the boot or shoe. A stationary rest, *q*, provided with a projecting lip, *r*, is secured to the under side of the frame *b*, the object of which is to allow the sole of the boot or shoe to rest against the under side of the said lip *r* during the upward motion of the feed-bar *g'*. The boot or shoe *s* is placed on a last, *t*, having a metallic plate, *t'*, on its bottom, against which the nail is riveted or clinched as it is forced down by the driver *f''*. The last *t* is secured to a suitable jack, *u*, that is operated by means of the treadle *v* and balance-weight *w*, or similar apparatus, in the ordinary way, so arranged that the boot or shoe may be turned and held in position for the purpose of receiving the nails in any desired place. To the under side of the feed-bar *g'* is secured an awl and feeder, *x*, as shown, for the purpose of feeding the material with the motion of rocking arm *h'*, and making a hole therein to receive the nail. *y* is a guide-roller, for the purpose of gaging the distance of the nails from the outer edge of the sole of the boot or shoe.

Having thus fully described the nature, construction, and operation of my invention, I wish to secure by Letters Patent, and claim—

1. The automatic feeding mechanism for feeding the shoe, as herein shown, in combination with the movable dies *o o* and the lip *r*, as and for the purpose set forth and described.

2. The lip *r*, in combination with the hollow

tube n , the ways m , the driver f' , and the movable dies $o\ o$, as and for the purpose set forth.

3. In combination with the driver f' , the movable dies $o\ o$ for receiving the nails, and a suitable support, u , on which the boot or shoe rests while automatically moved by the feeding mechanism, as and for the purpose herein shown and described.

4. In combination with the driver f' , the ways m , the fingers for picking the nails from the ways, and a suitable support, u , as and for the purpose set forth.

5. The combination of the guide y , as herein shown, with the movable dies $o\ o$ and the driver f' , for the purpose and in the manner set forth and described.

In testimony that I claim the foregoing, I have hereunto set my hand this 1st day of November, 1873.

HENRY DUNHAM.

Witnesses:
